S. A. XIPPA

HEATING DEVICE FOR AIR CIRCULATING FANS

Filed April 29, 1927

UNITED STATES PATENT OFFICE.

SOCRATES A. XIPPIAS, OF BUFFALO, NEW YORK.

HEATING DEVICE FOR AIR-CIRCULATING FANS.

Application filed April 29, 1927. Serial No. 187,421.

This invention relates to improvements in heating devices, and particularly to an electric heater for use on air circulating devices, such as ventilating fans.

In my Patent 1,577,280, dated March 16, 1926, I have disclosed a ventilating fan in which the fan wheel casing is of spherical shape, and provided at its poles with inlet openings, and at its medial horizontal portion with outlet openings. The main purpose of the present invention is to provide an electric heater which may be quickly attached to or detached from such a casing, although it will be obvious that the heater might be used with other types of ventilating fans and the like.

Another object of the invention is to furnish a heating attachment provided with resistance coils, and means for readily connecting such coils to the wires of a fan motor, so that the heater may be quickly attached and put in operation whenever desired.

Another object is to furnish an electric heater formed of hinged sections adapted to automatically interlock with a fan casing, when one of the hinged sections is moved relatively to the other one of such sections.

With the foregoing objects outlined and with other objects in view which will appear as the description proceeds, the invention consists in the novel features hereinafter described in detail, illustrated in the accompanying drawings, and more particularly pointed out in the appended claims.

Referring to the drawing,

Fig. 1 is a top plan view of the improved heater.

Fig. 2 is an enlarged side view of the same, and showing the heater attached to the fan casing.

Fig. 3 is an enlarged vertical sectional view of the heater, and illustrating the manner in which it embraces the fan casing.

Fig. 4 is an enlarged sectional view taken on line 4—4 of Fig. 1.

Fig. 5 is a side view partly in vertical section of the heater, in folded condition.

In the drawing, 1 designates a spherical fan casing of the type shown in my above mentioned patent, such casing having air inlet openings 2, and air outlet openings 3. Such casing is preferably made of upper and lower halves 4 and 5, connected together at their edges by a bayonet joint (not shown), arranged within a bead 6 which encircles the

spherical casing at its horizontal medial portion.

It is the main purpose of the present invention to provide an electric heater which may be readily and speedily attached to this fan casing, and adapted to heat the air as it is discharged substantially horizontally from the various outlet openings 3, around the fan casing. The heater may be of any appropriate construction, and for the purpose of disclosing the invention, I have illustrated a suitable embodiment of the heater. It includes a plurality of rings 7 of insulating material, spaced apart and connected by pins 8, and each ring is divided into a plurality of sections; the sections of the upper ring being hinged together at 9, and these hinges being arranged at diametrically opposite sides of the ring, to permit the sections at one side to be folded over on to the sections at the other side, as shown in Fig. 5.

Resistance coils 10 are arranged between the rings and are seated in grooves 11 of the latter, these coils, when in use, surrounding the fan casing. The ends of the coils are electrically connected to sockets 12 or the like, designed to receive pins 13 or the like, for connecting the coils to the line wires.

In actual practice, the pins may be connected to the wires which lead the current to the motor of the fan, but this forms no part of the present invention.

As best shown in Fig. 3, the upper and lower rings 7 have their inner surfaces converging toward the middle ring, so that these surfaces will conform to the spherical contour of the casing; the upper ring 7, in such case, resting on the outer surface of the casing, and thus supporting the heater.

The middle ring may be narrower than the other rings, as shown in Fig. 3, to accommodate the bead 6 on the casing, or, if desired, the middle ring might have its inner surface grooved to receive said bead, the bead in such case, also functioning to support the heater.

The opposite sides of the lower ring may, if desired, be provided with spring catches 14 to automatically lock the hinged sections in position, when the latter are moved into alignment, that is, into the position shown in Fig. 2.

From the above, it will be clear that in attaching the heater to the fan casing, the heater may be placed on the casing from

above, and at this time, the sections of the bottom ring 7 will be separated slightly. When the inner beveled surface of the upper ring engages or embraces the casing, the sections may then be moved into the position shown in Fig. 2, and the spring catches 14 will automatically lock the two halves of the heater together. Now the pins 13 of the line wires may be inserted in the sockets 12, and 10 the coils 10 will be heated, and this heat will be imparted to the air forced out through the openings 3.

From the foregoing disclosure, it is obvious that the invention may partake of many 15 forms, so long as it is capable of being readily attached to the casing, and of surrounding the latter, to permit the air discharged radially from the fan casing to be heated as it travels by the heater. When the heater is 20 attached, the fan not only circulates the air, but the air is heated during the circulation.

I am aware that various changes may be made in the details disclosed without departing from the spirit of the invention as 25 expressed in the claims.

What I claim and desire to secure by Letters Patent is:

1. An electric heater including a plurality of annular insulating rings, means connecting the rings together, resistance coils associated with the rings, and extending entirely around the heater, one of said rings having its inner surface beveled to permit the same to rest on a substantially spherical surface for supporting the heater. 30

2. An annular electric heater comprising superposed rings of insulating material, means connecting the rings and holding them in spaced relation, resistance coils annularly arranged between the rings, said rings forming a pair of members, and means hingedly connecting said members. 35

3. The combination with a substantially spherical fan casing, of an annular electric heater resting on said casing and comprising 40 rings of insulating material connected together in spaced relation, and heating wires connected to the insulating rings, and extending around said casing. 45

4. A combination as claimed in claim 3, 50 in which the heater is formed of sections hingedly connected together.

In testimony whereof I affix my signature.

SOCRATES A. XIPPAS.
